UNITED STATES PATENT OFFICE.

GEORGE MIZZELL, OF NEWPORT NEWS, VIRGINIA, ASSIGNOR OF ONE HALF TO A. T. MERRITT, OF NEWPORT NEWS, VIRGINIA.

REAMING-TOOL.

1,392,960.

Specification of Letters Patent. Patented Oct. 11, 1921.

Application filed January 18, 1921. Serial No. 438,131.

To all whom it may concern:

Be it known that I, GEORGE MIZZELL, a citizen of the United States, residing at Newport News, in the county of Warwick 5 and State of Virginia, have invented certain new and useful Improvements in Reaming-Tools; and I do hereby declare the following to be a full, clear, and exact description of the invention, such as will enable others 10 skilled in the art to which it appertains to make and use the same.

This invention relates to new and useful improvements in reaming tools, and more particularly to a reamer adapted for use in 15 countersinking openings in the shell plates, tanks and other heavy metal plates used in connection with the building of ships, the main object of the present invention being the provision of a reaming tool whereby the 20 cutting knife can be arranged in such a position as to permit the insertion of the reaming tool within the opening for reaming out the side of the opening opposite the operator, means being provided to arrange 25 the cutting blade in operative position after the tool has been extended through the opening.

In the reaming out of openings in tanks and similar structures it generally requires 30 the services of an operator upon the inside of the tank, with the tool in use at the present time, this operator on the inside arranging the cutting blade in position after the tool has been inserted through the opening 35 by the operator upon the opposite side and it is the main object of my invention to provide a reaming tool wherein the knife blade will be normally arranged within the confines of the tool so that it can be readily 40 inserted through an opening and then arranged in operative position for reaming out the opening upon the side opposite from which the operator is working.

A further object of my invention is the 45 provision of new and novel means whereby a single blade cutter can be readily operated to arrange the same within the tool when not in use and again re-arrange the same to extend the cutting blade to its operative 50 position, and furthermore providing means whereby when pressure is exerted upon the cutting blade, a suitable bearing will be provided for the blade to release the strain 55 of the cutting operation from the means which operates the blade.

With the above and other objects in view the invention consists in the novel features of construction, combination and arrangement of parts hereinafter more fully set forth, pointed out in the claims and shown 60 in the accompanying drawings in which:

Figure 1 is a longitudinal sectional view taken through my improved tool showing the blade in its operative position, and also illustrating the blade within the confines 65 of the tool in dotted line;

Fig. 2 is a similar view looking in a direction opposite that shown in Fig. 1;

Fig. 3 is a side elevation, parts thereof being broken away and illustrated in section; and

Fig. 4 is a transverse sectional view taken on the line 4—4 of Fig. 3.

Referring now more particularly to the drawings the numeral 1 indicates the body 75 member of my improved tool which may be formed of a single piece or in two separate pieces as desired. The body member 1 may be formed of steel or any other suitable material of this character and is provided at 80 its outer end with a slotted portion 2 in which the cutting blade 3 is adapted to operate. Extending longitudinally of the body member 1 and projecting into the slotted portion 2 at a central point is the longitudinal opening 4 in which is adapted to slide the operating rod 5, the outer end of which is pivotally connected to the knife 3 by means of the pivot pin 6. This rod 5 is moved within the opening 4 by means of the 85 pin 7 which is connected to the inner end of the rod 5 in any suitable manner and adapted to operate through a slot 8 formed in the body 1.

The outer end of the slotted portion 2 is 90 closed by means of a cap member 9 which is mounted upon the reduced outer end 10 of the body member 1 and provided with a central reinforced brace member 11, said brace member being disposed in alignment with the slot 2 so that when the cutting blade 3 is arranged in its operative position as shown in Fig. 1 the back of the cutting blade will abut against this brace member 11 and be securely held in its operative position 95 against the surface being operated upon. The cap member 9 is securely retained in position by means of the screw bolt 12 which is extended through the side walls of the cap and through the reduced portion 10 of 100

110

the body member 1 and the bracing member 11. Thus the several parts are securely retained in position and can be quickly and readily removed when it is desired to insert 5 a new knife blade or for any other purpose of this character.

In Fig. 1 I have illustrated the cutting blade 3 in an inoperative position in dotted lines and it will be noted that the blade when 10 in this position is entirely within the confines of the body of the tool and does not project beyond the outer surface of the body, but in full lines the blade is illustrated in its operative position and in order to 15 move the blade from one position to the other, a suitable arcuate groove 13 is formed in one face of the slotted portion 2 and the knife blade 3 is provided with a guide pin 14 adapted to operate within this groove so 20 that when the pin 7 is grasped by the operator for imparting sliding movement to the rod 5, the knife 3 will be forced inwardly or outwardly according to the movement of the rod and through the movement in either 25 direction, the pin 14 will follow in the groove 13 and when the pin reaches either end of the groove, the knife blade 3 will be either in an operative or an inoperative position. From this it will be apparent that 30 when the pin 14 is in the outer end of the groove the blade 3 will be disposed in operative position as shown in Fig. 1 in full lines, but when the pin is at the inner end of the groove the blade will be disposed in 35 an inoperative position as shown in dotted lines in Fig. 1. It will be understood that in the construction of various sized tools and blades, the relative positions of the pivot pin 6, the pin 14 and the groove 13 will be 40 changed accordingly so that when the blade 3 is actuated, through the medium of the operating rod 5, the guide pin 14 will follow within the groove 13 and force the blade 3 either to an operative or an inoperative position. Particular attention is directed to 45 the fact that when the blade is in its operative position as shown in Fig. 1, the outer end of the same abuts against the transverse bracing member 11 arranged within the end 50 portion 10 of the body and held in place by the cap 9 so that the force of the cutting of the blade against the work, is directed against this bracing member and thus removing the strain from the pivot pin 6.

55 It will be noted in Fig. 2 that the operating rod 5 is illustrated in a position extended sufficient to bring the knife blade 3 to an operative position and that the pin 7 has not reached the inner end of the slot 8 60 thus leaving sufficient space between the point to which the pin is arranged in its present position and the end of the slot to permit the rod 5 to be extended beyond the operating end of the tool so that the knife 65 blade 3 can be removed and a new one in-

serted. This operation is carried out by removing the screw bolt 12 so that the cap 9 can be readily removed from the end of the body and permit the blade member 3 to be removed from the slotted portion 2 as the 70 pin 14 can readily pass out the open end of the slot 13 and as the pivot pin 6 is not secured to the blade 3 in any way, however the blade can be readily removed.

In order to determine the required depth 75 of countersinking, a suitable scale 15 is arranged upon the outer surface of the body member 1 and in such a position, that the depth of countersinking can be readily noted by the operator when the thickness of the 80 material through which the blade is inserted is taken into consideration.

From the above description, taken in connection with the accompanying drawings it 85 will be readily apparent that I have provided a simple and durable tool particularly adapted for reaming out openings, and wherein the tool is especially used on openings where both sides of the openings are to be reamed thus eliminating the necessity of 90 the operator moving from one side of the object to the other or the assistance of a second operator upon the opposite side of the object as the plate 3 can be readily arranged within the tool as shown in dotted lines in 95 Fig. 1, the tool inserted in the opening and the blade 3 moved to an operative position and when the work is finished, the blade 3 can be returned to its inoperative position and the tool withdrawn from the opening. 100 Furthermore, should one of the blades 3 become broken or the operator wish to remove the same for inserting a new blade, the operation can be quickly and readily carried out. It will be understood that this tool 105 can be quickly and readily attached in any suitable manner to the usual machine in use at the present time for operating tools of this character.

110 I claim:

1. A tool of the class described including a body member having a longitudinal groove therein and a recessed portion at one end, a rod slidable in the groove, a cutting blade pivotally connected to one end of the rod 115 and normally disposed in the recess within the confines of the body of the tool and means for guiding the blade into a transversed position with respect to the tool body upon reciprocation of the rod.

2. A tool of the class described including a body member having a longitudinal groove therein and recessed at one end, a cutting blade pivotally connected to one end of the rod and normally disposed within the recessed portion within the confines of the body, an arcuate groove in one side wall of the recess, a guide pin carried by the knife blade and movable within said arcuate groove whereby upon reciprocating move- 130

ment of the rod, the blade will be moved to a transversed position with respect to the body of the tool as and for the purpose set forth.

5 3. A tool of the class described including a body, having a recessed portion at one end, a movable cutting blade normally disposed within the recess and arranged longitudinally of the body, one side wall of the recess
10 having an arcuate groove, a guide pin carried by the blade and movable within said groove and means pivotally connected with the blade for actuating the same whereby the blade may be moved either to a longitudinal
15 or a transverse position with respect to the body.

4. A tool of the class described including a body member having one end bifurcated, a cutting blade movably arranged within the bifurcation and means whereby said blade is 20 operated to dispose the same either longitudinally or transversely of the body of the tool, a removable cap member arranged over the bifurcated end of the body and a bearing member arranged within the cap and 25 adapted to be disposed within the outer end of the bifurcation to form a bearing for one end of the blade when disposed in a position transversely of the body.

In testimony whereof I affix my signature. 30

GEORGE MIZZELL.
